UNITED STATES PATENT OFFICE.

CHARLES WILLIAM MARDEN, OF PORTSMOUTH, NEW HAMPSHIRE.

DRAFT-REGULATOR.

1,371,800.

Specification of Letters Patent. Patented Mar. 15, 1921.

Application filed April 22, 1920. Serial No. 375,820.

To all whom it may concern:

Be it known that I, CHARLES W. MARDEN, a citizen of the United States, and a resident of the city of Portsmouth, in the county of Rockingham and State of New Hampshire, have invented a new and Improved Draft-Regulator, of which the following is a full, clear, and exact description.

This invention relates to improvements in draft regulators, an object of the invention being to provide automatic means for controlling the position of a damper in a smoke pipe, in accordance with the draft.

A further object is to provide a regulator of the character stated, which can be installed at a reasonable initial cost, and which will result in a saving of fuel, and maintain a fire at a predetermined rate of combustion, and which will prevent the overheating of stove or heater.

With these and other objects in view, the invention consists in certain novel features of construction, and combinations and arrangements of parts, as will be more fully hereinafter described and pointed out in the claims.

In the accompanying drawings:

Figure 1 is a diagrammatic plan view illustrating my invention.

Fig. 2 is a view partly in section and partly in elevation illustrating the device.

1 represents a stove or heater, connected by a smoke pipe 2 with a stack 3, and the latter provided with a dampered cold air inlet 4 and damper 5, as is customary in this art.

The damper 5 is made with an operating weighted crank arm 6 to which a cord 7, or other flexible connecting device is secured at one end, and is passed over pulleys 9 and connected to an operating lever 10.

The lever 10 is made with a knife edge fulcrum 11 on a post 12 projecting upwardly from a water tank 13. A bell or float 14 is positioned in the tank 13, with its lower open end sealed by the water 15 in the tank 13, and the upper end of the bell 14 is connected by a link 16 with one end of the lever 10.

A counterbalance weight 17 is suspended 50 from the other end of lever 10 and balances the bell 14.

A pipe 18 projects through the bottom of tank 13, and has its upper open end in the air space in bell 14. The other end of said 55 pipe 18 projects into the smoke pipe 2 and between the damper 5 and the stack 3 and is made with a curved end 19 pointing toward the stack.

An extremely small orifice 20 is provided 60 in the top of the bell 14 which serves as a leak or by-pass passage to permit a certain amount of air or gas to pass through the same. In other words, air may constantly enter the bell 14 through the orifice 20 and 65 by making this orifice small enough, it is apparent that varying suction in the pipe 18 will vary the pressure inside the bell.

The operation is as follows: The draft through the smoke pipe 2 causes a movement 70 of bell 14 by reason of the suction through the pipe 18. When this draft is normal, the bell remains stationary, but when the draft is excessive, the bell will be moved appreciably, and through the medium of the 75 lever 10 and cord 7 will close, or partially close the damper 5. Hence, the damper 5 can be set at any position desired, and if there is an excessive draft of air, it will cause the damper to move so as to maintain 80 just the checking action desired.

Various slight changes might be made in the general form of the parts described, without departing from my invention, and hence I do not limit myself to the precise 85 details set forth, but consider myself at liberty to make such slight changes as fairly fall within the spirit and scope of the appended claims.

I claim:

1. The combination with a stove, a smoke pipe connected therewith, a damper in the smoke pipe, and a crank arm on the damper, of a water-sealed bell, a lever fulcrumed between its ends and connected at one end 95 to the bell, a counterweight on the other end of the lever, a flexible connecting device operatively connecting the lever and the crank

arm, a pipe connecting the interior of the bell with the smoke pipe, said bell having an orifice in its top.

2. The combination with a stove, a smoke pipe connected therewith, a damper in the smoke pipe, and a crank arm on the damper, of a water-sealed bell, a lever fulcrumed between its ends and connected at one end to the bell, a counterweight on the other end

of the lever, a flexible connecting device operatively connecting the lever and the crank arm, a pipe connecting the interior of the bell with the smoke pipe, said last mentioned pipe having a curved end inside of the smoke pipe and pointing toward the outlet of the smoke pipe. 10 15

CHARLES WILLIAM MARDEN.
